UNITED STATES PATENT OFFICE.

WILLIAM H. HEAD, OF HOOKSET, NEW HAMPSHIRE.

DESIGN FOR A LOVING-CUP OR SIMILAR RECEPTACLE.

45,632.

Specification for Design.

Patented Apr. 21, 1914.

Application filed February 7, 1914. Serial No. 817,353. Term of patent 3½ years.

To all whom it may concern:

Be it known that I, WILLIAM H. HEAD, a citizen of the United States, residing at Hookset, in the county of Merrimack and State of New Hampshire, have invented a new, original, and ornamental Design for a Loving-Cup or a Similar Receptacle, of which the following is a specification, referring to the given accompanying drawing, forming a part thereof.

The figure shown in the drawing is a perspective view of a loving-cup showing my new design.

I claim—

The ornamental design for a loving-cup or a similar receptacle, as shown.

WILLIAM H. HEAD.
